TENNIS NET

Leslie L. Appleyard, Chicago, Ill., assignor to R. J. Ederer Company, Chicago, Ill., a corporation of Illinois

Application August 26, 1932, Serial No. 630,572

7 Claims. (Cl. 273—29)

This invention relates to a net construction, particularly to the construction of a net intended for use as a tennis net. It has for one object to provide a construction whereby the upper edge of the tennis net is strengthened. 5 Another object is to provide means in a tennis net having a reinforced upper edge whereby the edge of the net itself is strengthened and whereby its attachment to the reinforcing is strengthened. 10 Other objects will appear from time to time in the course of the specification and claims.

This invention is illustrated more or less diagrammatically in the accompanying drawings, wherein—

15 Figure 1 is an elevation with parts broken away and parts in section showing a portion of the net;

Figure 2 is a transverse vertical section taken at line 2—2 of Figure 1;

20 Figure 3 is a sectional view similar to Figure 2, showing a modified form;

Figure 4 is a view generally similar to Figure 2, showing a further modified form;

25 Figure 5 is a view generally similar to Figure 1, showing the modified form of Figure 4.

Like parts are designated by like symbols throughout.

The net is formed of a plurality of vertical cords A, A¹ and a plurality of horizontal cords A¹. 30 They are woven or knotted together to form the netted fabric. In making the tennis net a portion of the netted fabric is bent or folded down upon itself. In the particular form shown herewith the folded portion comprises the width of three meshes. This folded portion is indicated generally as at X. The fold preferably occurs at one of the horizontal threads or cords A¹. The portion of the net which is overlain by the folded portion is indicated generally as at Y.

40 To support the upper edge of the net a rope or cable B is used. This may be of any suitable size or shape or material. A reinforcing and attaching means is provided which comprises a fabric frequently of canvas or other relatively strong and tightly woven material. As shown, it is formed of two sections C, C¹, which are folded together with their lower edges turned in as at C² C², respectively. The upper horizontal cord A¹ at which the fold occurs is placed between the 45 portions C, C¹ of the reinforcing upper edge member. The lower edges of the reinforcing member are joined by stitching D which comes below the horizontal cord A¹ and thus fastens the reinforcing and the net together. A second line of stitching D¹ may be used. This additionally fastens together the sections C C¹ of the upper member and in the form shown in Figures 1 and 2 it is positioned above the upper horizontal cord A¹ so that in that form of the invention this cord is 50 fastened between two rows of stitchings which

also fasten together the upper edging member. As an additional reinforcement a grommet E may be used. Such grommets may be used at the ends of the upper reinforcing member or at suitable distances throughout the length of this member. As shown, one of them is adjacent the end of the net and is positioned between the lines of stitching D, D¹ and below the upper cord A¹ so that it serves as an additional member by means of which the cord A¹ is fastened within 10 and held to the reinforcing strip C, C¹.

15 The form of the invention illustrated in Figure 3 differs from that shown in Figures 1 and 2 only with respect to the stitching. Instead of the arrangement shown in the first two figures, two rows of stitching F F¹ join the members C and C¹ and they are both below the cord A¹ which is embraced between the members C, C¹.

20 In both forms of the invention the outer ends of the net are preferably reinforced by stitching or knitting or otherwise as indicated at F. This reinforcing may be accomplished by running a chain stitch along the end of the net or in any other manner. Since the net is folded upon itself along one of its horizontal cords A¹ the 25 meshes of the two portions where they overlap coincide or register and the lower edge of the folded portion coincides with one of the horizontal cords A¹. At this point a third horizontal cord G may be run across the net and used as 30 a fastening and tying member, being tied about the intersections of the meshes as at G¹ G¹. The other mesh intersections might also be tied.

35 The form of the invention shown in Figure 4 involves the same parts as those shown in the earlier figures. The difference is merely that the parts are fastened together somewhat differently. A further reinforcement is provided for the sides and the bottom of the net and the rope at the top of the net is fastened differently. The net 40 itself and the method of folding it is the same as that shown in Figure 1. Instead, however, of the stitching, binding or knitting F at the edge of the net, a tape or fabric reinforcing H may be used. A reinforcing cord H¹ may be used 45 as the cord G is used in Figure 1, but a similar reinforcing cord H¹ runs preferably up and down along the edges of the net so that they are reinforced by a cord H¹, tied to the meshes as at H², in addition to the reinforcing given by the cord H¹ where it is tied to the overlapping horizontal 50 cords A¹ A¹ of the folded portion of the net.

55 In the form of the invention shown in Figure 5, the sides of the net and the fastening cord H¹ are all enclosed in the fabric or tape reinforcing H, which is wrapped about them and stitched in place by a row of stitches H³ which to some degree pass through the cords A¹ A¹ and so additionally fasten the tapes to the net.

60 As shown in Figure 5 a reinforcement is pro-

vided for the bottom of the net, which includes a cord I which runs across the net and is fastened to the lowest cord A¹ in any suitable manner. It may be tied thereto by making knots 5 in the vertical cords A. In some cases the cord I need not be fastened directly to the cords of the net but is merely enclosed in a tape or fabric reinforcing I¹ which is fastened to the lower part of the net by stitches I². Thus if the cord 10 and the net are not fastened together, each is fastened to the reinforcing tape.

At its upper edge the net, in the form shown in Figure 5, is folded exactly as in Figure 1, but in this case, instead of being free from the 15 rope B it is fastened thereto, preferably by a tying cord J which runs generally parallel with the upper horizontal cord A¹ of the net and is tied to it at the ends of the meshes in knots J¹. Thus the cord E, instead of being free to slide 20 in the reinforcing fabric portion C, and free to slide with respect to the net, is fastened to it, and only a single row of stitching D is preferably used to fasten the reinforcing fabric C together and to engage and grip the vertical cords A of the 25 net.

Of course, the construction of the upper edge of the net shown in Figures 4 and 5, in which the net is tied to the rope and the rope and net are then enclosed in the reinforcing C, might be used 30 without the reinforced sides, as shown in Figure 5, and without the reinforced bottom as shown in that figure, and while the net may as a whole be made as shown in that figure, its construction is not limited to that particular combination and 35 changes such as those suggested with respect to either the sides and the bottom or both of them might be made without departing from the spirit of the invention and in all of the forms of the invention the reinforcing cords G and H¹, which 40 are shown where edge portions or joining portions of the net occur, might be omitted or cords of a different type or knots of different types might be used.

If the net is used as shown in Figures 4 and 5 45 but without the bottom reinforcing tape or fabric I¹, then the net will, of course, be fastened directly to the cord I, so that this cord will serve as a reinforcing and fastening member for the bottom of the net, whether or not the tape or fabric I¹ 50 is used.

A further change which is in effect a modification of the form shown in Figures 4 and 5 is that in which the tying cord J and the knots J¹ are omitted and the upper rope B is woven or threaded 55 through the meshes of the net. Thus it is below the uppermost horizontal cord A¹ and lying in the upper row of meshes formed at the fold of the net. Where this is done the net and the rope B may be tied together either by a cord similar to 60 the cord J or by any other suitable tying means and the reinforcing member C and the stitching D will be the same.

I claim:

1. In a tennis net, a netted fabric forming the 65 net proper, said fabric being folded upon itself and providing a portion extending downwardly a substantial distance from its upper edge to receive the impact of the balls, and a binding along both sides of the upper edge of the net, engaging the 70 upper edge of the net generally at the fold, there being a plurality of lines of stitches in the binding, one positioned upon one side and the other

upon the other side of the upper folded edge of the net.

2. In combination in a tennis net, a netted fabric folded upon itself and providing a portion extending downwardly a substantial distance from its upper edge to receive the impact of the balls, and a binding along the upper edge of the net, said binding engaging and enclosing the fold of the net, and a plurality of lines of stitching through the binding fastening the edges of the binding together, one line of stitching being above the fold of the net and the other being below it, and an attaching member for the lower edge of the folded portion of the net, comprising a cord of the same size as the cords of the net, running 15 across the net and formed into knots fastening the edge of the folded portion of the net to the main fabric of the net.

3. In a tennis net, a netted fabric forming the net proper, said fabric being folded upon itself 20 and providing a portion extending downwardly a substantial distance from its upper edge to receive the impact of the balls, and a binding along both sides of the upper edge of the net, engaging the upper edge of the net generally at 25 the fold, and a line of stitching in the binding, positioned below the folded edge of the net.

4. In a tennis net, a netted fabric forming the net proper, said fabric being folded upon itself and providing a portion extending downwardly 30 a substantial distance from its upper edge to receive the impact of the balls, in combination with a rope, means for fastening said rope to said net, and a binding along both sides of the upper edge of the net, enclosing the upper edge 35 of the net and the rope, and stitching joining the binding and engaging the net to prevent its removal from the binding.

5. In combination in a tennis net, a netted fabric forming the net proper, said fabric being 40 folded upon itself and providing a portion extending downwardly a substantial distance from its upper edge to receive the impact of the balls, so that the meshes of the folded portion register with the meshes of the main body of the net, 45 and a reinforcing member arranged generally parallel with the joining edges of the net and knots in the reinforcing member tying the meshes of the net together.

6. A tennis net formed of a wide meshed fabric, 50 said fabric being folded and reversed upon itself and providing a portion extending downwardly a substantial distance from its upper edge to receive the impact of the balls to provide an extended reinforced portion adjacent its upper edge, and a 55 binding embracing the folded edge and extending above it, and means for fastening the binding to the folded edge of the net.

7. A tennis net formed of a wide meshed fabric, 60 said fabric being folded and reversed upon itself and providing a portion extending downwardly a substantial distance from its upper edge to receive the impact of the balls to provide an extended reinforced portion adjacent its upper edge, and a binding embracing the folded edge and 65 extending above it, and means for fastening the binding to the folded edge of the net, and a rope within said binding and means for fastening the lower edge of the folded reinforcing portion 70 of the net to the main body of the net.
